Co-pending application—Hirst et al. U.S. Appl. No. 29/353,870, filed Jan. 15, 2010; entitled: Pump Dispenser.

* cited by examiner

Primary Examiner—Catherine Tuttle

(74) Attorney, Agent, or Firm—Milton L. Honig

(57) **CLAIM**

The ornamental design for a pump dispenser, as shown and described.

DESCRIPTION

FIG. 1 is a top, front and left side perspective view of our pump dispenser;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dashed lines shown in FIG. 7 are included for the purpose of illustrating a portion of the pump dispenser that forms no part of the claimed design.
